DESIGN FOR A SCREEN FOR AN AUTOMOBILE RADIATOR

Ben Wengard, Waterloo, Iowa

Application August 21, 1936, Serial No. 64,510

Term of patent 7 years

To all whom it may concern:

Be it known that I, Ben Wengard, a citizen of the United States, residing at Waterloo, in the county of Blackhawk and State of Iowa, have invented a new, original, and ornamental Design for a Screen for an Automobile Radiator, of which the following is a specification, reference being had to the accompanying drawing, forming a part thereof.

The figure is a front elevation, showing my new design, of a screen for an automobile radiator.

The dominant features of the design are shown in solid black lines in the drawing.

I claim:

The ornamental design for a screen for an automobile radiator, as shown and described.

BEN WENGARD.
